UNITED STATES PATENT OFFICE

120,904

DESIGN FOR AN ILLUMINABLE WHATNOT

Hartsell Walter Beaver, Statesville, N. C.

Application March 12, 1940, Serial No. 90,862

Term of patent 7 years

To all whom it may concern:

Be it known that I, Hartsell Walter Beaver, a citizen of the United States, residing at Statesville, in the county of Iredell and State of North Carolina, have invented a new, original, and ornamental Design for an Illuminable Whatnot, whereof the following is a specification, reference being had to the accompanying drawing, forming part thereof.

In the aforesaid drawing:

Fig. 1 is a perspective view of an illuminable whatnot showing my new design;

Fig. 2 is a view in side elevation thereof, to a somewhat reduced scale, the top portion being broken away for convenience of illustration;

Fig. 3 is a top plan view thereof;

Fig. 4 is a fragmentary underneath perspective view of one of the shelves, showing the appearance of the lamp unit.

I claim:

The ornamental design for an illuminable whatnot, as shown.

HARTSELL WALTER BEAVER.
